UNITED STATES PATENT OFFICE.

MYLES F. BRADLEY, OF FLINT, MICHIGAN.

DESIGN FOR A BADGE, BUTTON, EMBLEM, OR ARTICLE OF SIMILAR NATURE.

56,690.

Specification for Design.

Patented Nov. 30, 1920.

Application filed September 14, 1918. Serial No. 254,144. Term of patent 3½ years.

To all whom it may concern:

Be it known that I, MYLES F. BRADLEY, a citizen of the United States, residing at Flint, in the county of Genesee and State of Michigan, have invented a new, original, and ornamental Design for Badge, Button, Emblem, or Article of Similar Nature, of which the following is a specification, reference being had to the accompanying drawing, forming part thereof.

The figure is an elevation of a button, showing my new design, the upper diagonal bar of which is red, the lower blue, and the space between is white.

I claim:

The ornamental design for a badge, button, emblem, or article of a similar nature, as shown, and described.

MYLES F. BRADLEY.
